US0D1087283S

(12) **United States Design Patent** (10) **Patent No.:** **US D1,087,283 S**
(45) **Date of Patent:** **** Aug. 5, 2025**

(54) **PERSONAL SAFETY DEVICE**

(71) Applicant: **Arlo Technologies, Inc.**, Carlsbad, CA (US)

(72) Inventors: **Scott McManigal**, Newport Beach, CA (US); **Soo Youn Park**, Lake Forest, CA (US)

(73) Assignee: **Arlo Technologies, Inc.**, Carlsbad, CA (US)

(**) Term: **15 Years**

(21) Appl. No.: **29/857,710**

(22) Filed: **Oct. 25, 2022**

(51) **LOC (15) Cl.** **22-02**

(52) **U.S. Cl.**

USPC **D22/117**

(58) **Field of Classification Search**

USPC D22/117, 199; D9/300, 302, 448; D28/91.1; D10/104.1, 106.1; D3/300, D3/203, 207

CPC F41H 13/0031; F41H 13/0037; F41H 13/0018; F41H 13/0025; F41H 13/0012; F41H 13/0006

(57) **CLAIM**

The ornamental design for a personal safety device as shown and described.

DESCRIPTION

FIG. 1 is a top, front, right side perspective view of a personal safety device showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is a bottom, front, right side perspective view thereof.

The broken lines depict portions of the personal safety device that form no part of the claimed design.

1 Claim, 8 Drawing Sheets
